UNITED STATES PATENT OFFICE.

JOHN E. BUCKLIN, OF WASHINGTON, DISTRICT OF COLUMBIA, ASSIGNOR OF
ONE-HALF TO ROBERT E. MORRIS, OF SAME PLACE.

HORSESHOE-MACHINE.

SPECIFICATION forming part of Letters Patent No. 450,597, dated April 14, 1891.

Application filed August 23, 1890. Serial No. 362,840. (No model.)

To all whom it may concern:

Be it known that I, JOHN EDWIN BUCKLIN, a citizen of the United States, residing at Washington, in the District of Columbia, 5 have invented certain new and useful Improvements in Horseshoe-Machines; and I do hereby declare the following to be a full, clear, and exact description of the invention, such as will enable others skilled in the art to which it appertains to make and use the same.

This invention relates to certain new and useful improvements in horseshoe-machines; and it consists substantially in such features of arrangement, construction, and combinations of parts as will hereinafter be more particularly described and claimed.

The object of the invention, broadly stated, is to provide a horseshoe-machine which shall at one operation effect the cutting of the 20 blank and both the bending and swaging of the shoe, substantially as will hereinafter be more fully understood on reference to the accompanying drawings, in which—

Figure 1 is a side elevation of a horseshoe-machine embodying the features of my invention, and Fig. 2 is a vertical longitudinal sectional elevation taken on the line $x-x$ of Fig. 3. Fig. 3 is a front elevation of the machine with the oscillating or swinging anvil detached or broken off, so as to more clearly represent the construction and operation of the several parts. Fig. 4 is a side view in detail of a certain feature of the machine and which will be more fully explained hereinafter. 35 Fig. 5 is a detail in perspective of the reciprocating guide-plate.

In carrying my invention into effect I provide a machine in the front of which is a plate or frame that is caused to reciprocate vertically between the two sides or walls of the machine, and this plate supports and carries with it both the cutter for the blank and the bending or shaping rolls which bend the blank around the forming-die. This frame also supports at a line centrally intermediate of the shaping-rolls a vertical tube or sleeve which is slotted diametrically for a suitable distance from its lower end, and a spiral spring is contained in said sleeve, against the action of 45 which at proper intervals a movable finger is caused to be held down over the forming-die,

so as to accurately center the cut blank and permit the shaping-rolls to properly effect the shaping of the shoe. The said movable finger works in the slotted end of the tube, 55 and the arrangement thereof is such with respect to the connection between the vertically-reciprocating plate and the operating-shaft of the machine, that immediately the blank is cut the said finger is brought into 60 position for holding said blank. As soon as the shaping-rolls effect the bending of the blank around the forming-die the vertically-reciprocating plate or frame which carries such rolls begins to recede upwardly, and at 65 this time a pivoted oscillating or swinging anvil begins to move inwardly toward the forming-die. This swinging anvil carries the swage which presses the shoe into form; the said shoe being both creased and pressed into 70 proper configuration by its action. Just at the time the swage reaches the forming-die the finger, which has been held down upon the blank, will be lifted by virtue of the vertically-reciprocating plate having receded upwardly to its utmost limit, and at this time also the forming-rolls will have been restored to their former positions, ready to again be carried down on the next movement of the reciprocating plate. 75

Beneath the shaping-rolls and the cutter for the blank, and in a plane coincident with the plane in which the reciprocating plate or frame moves, is a guide-plate for receiving and holding the bar from which the blank is 80 cut, which guide-plate is also made to reciprocate vertically, so as to be carried downward immediately the blank is cut from the bar; thus enabling the reciprocating plate or frame to move downward with the shaping- 85 rolls for bending the blank around the forming-die. 90

The cutter for the blank has a stop opposite to it, and both the cutter and stop are taken or received into slots in the upper edge of the 95 guide-plate as the reciprocating frame moves downward, and it is in this way that the said guide-plate is operated, the downward movement of the latter taking place a little after the frame has started and immediately the blank is cut from the bar. The upper or return movement of the guide-plate is effected 100

through the action of a spring simultaneously with the upward or return movement of the plate or frame.

During the severance of the blank from the bar it is of course necessary that the guide which holds the bar shall be sustained against the force necessary to effect the cutting; and it is further necessary, from the construction resorted to, that as soon as the blank has been 5 to cut the guide shall be carried down out of the way of the forming-rolls. To provide for this I employ a stationary slotted tube extending upwardly from the base of the machine and containing a spiral spring, and 10 working in this tube against the action of the spring is a sleeve which fits around a rod pendent from the guide-plate on one side at its lower portion. This sleeve is adapted to turn or rotate on the rod, and is formed with 15 a nose or projection which normally rests upon the upper edge of the stationary tube just to one side of the slot thereof. In this position of the parts the guide-plate will be sustained in position to enable the cutter to do 20 its work; and then immediately the blank has been cut there will be a lever actuated from the drive-shaft of the machine to move against the nose or projection on the sleeve, and thereby turn the sleeve and bring such nose 25 or projection into the slot of the tube in which the sleeve works. At this time the guide-plate commences to move downward with the reciprocating frame, and as soon as the bending and swaging of the shoe has been 30 completed the parts will all be restored as originally. When the nose of the sleeve again reaches the upper edge of the slotted tube, it is forced over to one side of the slot by a spring-actuated pin which works against the 35 same.

Reference being had to the several parts of the drawings by the letters marked thereon, A A represent the two sides or walls of the machine, in which the main driving-shaft B 45 has its bearing, as shown. The said shaft is provided centrally between the two walls or sides with an eccentric C, which is movably connected to one end of a walking-beam D, that is supported by a standard E, the other 50 end of said walking-beam being in movable connection with a link F, which in turn is in movable connection with the vertically-reciprocating plate or frame G, which works on guides a a, bolted or secured to the front edges 55 of the walls or sides A A at their upper portions. The said vertically-reciprocating frame or plate is formed or provided at its lower portion with hollow sleeves or guides b b, oppositely arranged to each other, and in these 60 guides are located or arranged the horizontal blocks or carriers c c, in which the shaping or bending rolls d d have their bearing, as shown.

Secured to the inner edges of the opening l 65 in the vertically-reciprocating plate are the flat springs d' d', which extend down behind the shaping-rolls and bear outwardly against

the blocks or carriers with the tendency of forcing them outward or apart. The outer ends of these blocks or carriers work against 70 the inclined faces of the guides e e, and when the reciprocating plate or frame G moves downwardly it will be apparent that the sliding blocks or carriers will be forced together inwardly and the bending-rolls caused to work 75 around the outer surface of the forming-die H with powerful effect. On the return or upward movement of said plate or frame the sliding carriers d d will again be forced outward, together with the rolls. 80

The forming-die H is made integral with a plate I firmly set in the machine and backed or re-enforced by a brace J, secured between the two sides or walls A A, so as to furnish 85 enough resistance to the action of the swage.

One of the sleeves or guides b is formed or provided with a cutter f for the blank, and the other is formed or provided with a stop g, against which the end of the bar from which the blank is cut abuts, and after the initial 90 downward movement of the vertically-reciprocating plate or frame G, at which the blank is cut, the said cutter and stops by the continued downward movement of said plate enter notches i i, formed in the upper edge of 95 the guide-plate, and thus is said plate forced downward. The said guide-plate is formed or provided at its lower portion with a rod h, which works in a tube j, against the action of a spiral spring k, contained in said tube, 100 and after the plate has gone downward the extent of its limit it will be again forced upward by the spring simultaneous with the upward movement of the reciprocating frame or plate G. 105

The heated bar from which the blank is cut is supposed to be fed to the machine from the side (left-hand side in the drawings) and in line with the guiding-spaces m m of the guide-plate, which spaces are formed by turning over the side edges of the plate. (See Fig. 5 for a more complete understanding.) These spaces receive the end of the bar as it is inserted.

In order to sustain the guide-plate from 115 downward movement until after the blank has been cut, I provide a stationary tube o, extending upwardly from the base M of the machine, the said tube being open at its upper end and slotted, as at n, for a suitable distance from said upper end. (See Fig. 4.) In this tube is contained a spiral spring o, and working downward in the tube against the action of the spring is a sleeve p, which fits upon a rod or pin q pendent from the lower 120 portion of the guide-plate at one side, and is adapted to turn on said rod or pin. This sleeve is provided with a nose or projection r, which rests upon the upper edge of the slotted tube when the guide-plate is up, thus 125 firmly sustaining the plate while a blank is 130 being cut from the bar. Immediately the blank is cut a bent arm or lever P will be actuated by a cam s (see Fig. 2) on the drive-

shaft to move forward, so that its lower end will come in contact with the nose *r* and thereby turn the sleeve *p* around on the rod *q* until said nose is carried into the slot *n*, whereupon the rod and sleeve will be carried down into the tube by descent of the guide-plate. As the guide-plate is again caused to recede upwardly, the spring *o* will at the same time react and the nose or projection be again lifted over the upper edge of the slotted tube. The lever *P*, in pushing against the nose *r*, does so against the action of a spring-bolt *t*, that works in a sleeve *u*, supported by a bracket *v*, that is secured to the lower portion of the guide-plate, as shown in Fig. 4. The said bracket is formed integral with and at right angles to a slotted guide *w*, which moves on a pin or screw *x*, and which serves to maintain the relative positions of the parts. It is this spring-bolt which serves to again force the nose *r* over onto the upper edge of the tube *O* after said nose has been raised above the upper extremity of the slot *n*. The upper portion 2 of the lever *P* works through a stationary guide *z*, and the rear end of said lever is formed or provided with a nut or head 4, between which guide and head is arranged a spiral spring 5, surrounding the lever, which spring becomes compressed when the lever is urged forward by the cam on the drive-shaft, and then after the cam has passed and the lever has effected its function by working against the nose *r* on the sleeve the said spring expands and causes the return of the lever in an obvious manner.

R represents a tube that is screwed or bolted to the face of the vertically-reciprocating plate centrally thereof, the said tube being slotted diametrically for a suitable distance from its lower end, as shown at *y*, so as to receive and accommodate the movement of a branch *z* of pendent finger 7, the said finger acting to move down upon the blank immediately it has been cut from the bar, and to hold such blank upon the forming-die until after the shaping-rolls have effected the bending. As the reciprocating plate or frame descends, the slotted tube moves down upon the branch *z* of finger 7, and such finger remains resting upon the blank over the top of the forming-die until the reciprocating plate again ascends, whereupon the said finger is lifted by the bottom of the tube. The lifting of the finger takes place just at the time the swinging anvil *S* has carried its swage 8 up to shape or crimp the shoe. This swinging anvil has its bearings between the two sides *A A* at the forward end of the machine, as shown, and is operated to move forward toward the forming-die at the proper intervals through the medium of eccentrics 9 9 on opposite sides of the machine and their connecting arms or rods 10 10.

Located in suitable position in front of the machine at its forward end is a curved discharge-chute *V* onto which the shoes fall, and

from which they are discharged as fast as they are turned out from the machine.

It is thought that from the foregoing description the construction, arrangement, and operation of my invention will be thoroughly understood; but it may be added that no second heating of a blank is ever required in making a shoe from this machine, and further stated that the several parts are so arranged that the cutting, bending, and swaging of the shoe is effected in rapid succession by a single operation of the machine, or, in other words, by a single revolution of the driving-shaft.

Having thus described my invention, what I claim as new, and desire to secure by Letters Patent, is—

1. In a horseshoe-machine, the combination of a vertically-reciprocating plate and a pair of sliding blocks or carriers provided with bending or shaping rolls and adapted to be reciprocated back and forth on movement of the plate, substantially as described.

2. In a horseshoe-machine, the combination of a vertically-reciprocating plate, a pair of reciprocating blocks or carriers provided with bending or shaping rolls, and a pair of inclined guides against which the outer ends of the carriers move, substantially as described.

3. In a horseshoe-machine, the combination, with the vertically-reciprocating plate and a pair of reciprocating blocks or carriers provided with bending or shaping rolls, of springs for maintaining said carriers normally outward, substantially as described.

4. In a horseshoe-machine, the combination, with the vertically-reciprocating plate and a suitable forming-die, of a vertically-operating finger adapted at intervals to be carried down upon the die to hold the blank and again lifted after the blank has been bent, substantially as described.

5. In a horseshoe-machine, the combination, with the vertically-reciprocating plate and the forming-die, of the slotted tube secured to said plate and containing a spring, and the vertically-operating finger working in the slot of the tube, substantially as and in the manner set forth.

6. In a horseshoe-machine, the combination, with the vertically - reciprocating plate or frame, of a vertically-operating guide-plate arranged beneath the frame and adapted to be operated thereby, substantially as described.

7. In a horseshoe-machine, the combination, with the vertically - reciprocating plate or frame and the vertically-operating guide-plate for receiving and holding the bar from which the blank is cut, of a cutter for said blank and a stop against which the end of the blank abuts while being cut, substantially as described.

8. In a horseshoe-machine, the combination of a forming-die, a cutter for the blank, an automatic finger for holding the blank upon the forming-die, a guide for receiving the bar from which the blank is cut, a pair of shap-

ing or bending rolls, and a swage, substantially as described.

9. In a horseshoe-machine, the combination, with the vertically-reciprocating plate or frame and the cutter and stop, of the vertically-moving guide-plate having notches in its upper portion adapted to receive the cutter and stop on the downward movement of said frame, substantially as described.
10. In a horseshoe-machine, the guide-plate having its side edges turned over to form the spaces *m m* and being also formed with the notches *i i*, substantially as described.
11. In a horseshoe-machine, the combination, with the guide-plate and blank-cutter, of means for temporarily holding or supporting said plate up to the cutter and means for automatically releasing said support at the time said cutter has completed its work, substantially as described.
12. In a horseshoe-machine, the combination, with the vertically-operating guide-plate, of the slotted tube *O*, in which is contained a spring, the rod *p*, pendent from the frame, the sleeve adapted to turn on the rod and having the nose or projection *r*, and the

lever *P* with its spring, all substantially as described.

13. In a horseshoe-machine, the combination, with the vertically-operating guide-plate and the slotted tube *O*, of the sleeve having the nose *r*, the lever *P*, the spring-bolt *t*, supported in a bracket from the guide-plate, and the slotted guide *w*, substantially as described.

14. In a horseshoe-machine, the combination, with a stationary forming-die, of a swinging anvil carrying a swage and operating at intervals to move up to said forming-die, substantially as described.

15. In a horseshoe-machine, the combination, with the drive-shaft, of a swinging anvil carrying a swage, and means for operating said anvil from the shaft, substantially as described.

In testimony whereof I affix my signature in presence of two witnesses.

JOHN E. BUCKLIN.
